UNITED STATES PATENT OFFICE

JAMES IRONSIDE, OF DETROIT, MICHIGAN, ASSIGNOR, BY MESNE ASSIGNMENTS, TO CLAYTON & LAMBERT MANUFACTURING CO., OF DETROIT, MICHIGAN, A CORPORATION OF DELAWARE

COMBINED STARTING AND MIXING CHAMBER FOR LIQUID-FUEL BURNERS

Application filed June 13, 1928. Serial No. 284,922.

This invention relates to a combined starting and mixing chamber for liquid fuel burners, and has to do particularly with that type of liquid fuel burner wherein the generator tube and the mixing chamber and/or the starting member are adapted to be moved relative to each other to effect starting.

The object of the present invention is the provision of a combined starting and mixing chamber of extremely compact, simple and inexpensive design, and which is preferably adapted to receive a generating tube and to cooperate with said tube in a novel manner in two different positions of said tube. More specifically, the present invention relates to the provision of an integral starting and mixing chamber which is cylindrical in shape, a portion of said cylindrical member being cut away and a portion opposite said cut away part being formed in the shape of a priming cup whereby this cylindrical member may be rotated about its axis to starting position and then rotated 180° to mixing and normal operating position. This novel cylindrical structure makes it possible to form a combined starting and mixing chamber which has very few parts which require machining, and which is very inexpensive to manufacture and assemble.

Other features of this invention include the novel manner of positioning the cylindrical element within an integral housing which housing serves in combination with the cylindrical element as a mixing and conducting member, and also serves as a means of conducting the air to a point where it is mixed with the vaporized fuel. Another feature has to do with the peculiar formation of the cylindrical starting and mixing member and particularly with the formation of one end thereof which serves as a deflector member for initially deflecting the vaporized fuel issuing from the generator tube backwardly against said tube in the form of a blast of flame to accelerate the heating thereof.

In the drawings:

Fig. 1 is a vertical sectional view of my combined starting and mixing chamber, as applied to a typical stove structure and show-

ing the generator tube and cylindrical member in correct starting position.

Fig. 2 is a view similar to Fig. 1 but showing the cylindrical starting member rotated 180° about its axis so as to completely enclose the supporting housing and also showing the generating tube moved to normal operating position.

Fig. 3 is a plan view of the structure shown in Fig. 1.

Fig. 4 is an end elevation of the structure shown in Fig. 3.

Fig. 5 is a sectional view taken on line 5—5 of Fig. 1.

In illustrating the present invention I have shown the same as being embodied in connection with a stove structure of the type having a movable generator tube adapted to be heated in normal operating position by a burner positioned beneath said generating tube, but it will be understood that this invention is not limited to the specific structure shown, but may be broadly embodied in any liquid fuel burning apparatus regardless of the particular movement between the generator tube and the starting structure, and regardless also of the manner of heating the generator tube after initial starting.

The housing for embodying the starting element may be generally designated 1, and is preferably an integral casting having a certain portion thereof designed to rotatably receive a cylindrically shaped starting member which may be generally designated 2. In the particular embodiment shown, the housing 1 is provided with air inlets 3 which extend forwardly and upwardly and merge into a common chamber which has an inlet opening 4 for receiving and positioning the generator tube 5.

This generator tube 5 may be of any standard type and as shown comprises a tube enlarged at its outer end and provided with spiral coils of wire therein for feeding the liquid fuel by capillary action, and also provided with a suitable jet block 6 for directing the vaporized fuel forwardly in a fine stream. A suitable burner 7 may be positioned beneath the generator tube 5 whereby to maintain the same heated to the proper degree.

during the normal operation of the generating apparatus.

The cylindrical starting unit 2 is preferably made up of stepped cylindrical sections; in other words, the front of said cylindrical unit is formed of a cylindrical section of relatively small diameter which may be designated 8, and this section 8 is preferably cut away, as shown at 9 in Fig. 2. The other portion 10 of the tube is of somewhat larger diameter and may be designated 10. This enlarged part of the cylindrical member is so designed as to form a priming cup 11. This portion 10 is also cut away, as best shown in Figs. 1 and 2, with the exception of a portion 12 at the extreme end thereof, which portion 12 forms a journal for the outer end of the member 2. The member 2 is preferably cast integrally, and the end portion 12 is provided with a suitable arcuate depression 13 which serves as a blast deflector, as will be later described.

The housing member 1 has a portion thereof which is cylindrical in shape, as best shown in Figs. 4 and 5, and these portions comprise a relatively small cylindrical portion 15 which serves as a bearing for the inner cylindrical portion 8 of the member 2, and an enlarged cylindrical portion 16 which serves as a bearing for the cylindrical portion 12 of the member 2. The cylindrical side walls of the housing 1 and the cylindrical portion 10 of the member 2 preferably extend upwardly slightly past the center, as shown in Fig. 5, whereby when the cylindrical member 2 is rotated to the position shown in Fig. 2, the two cylindrical portions will cooperate and overlap to form a complete enclosed circuit.

Suitably secured to the head 12 of the cylindrical member 2 is an arm 17 having a suitable handle 18 with lugs 19 at each end thereof. The member 17 is adapted to extend horizontally to the right, as shown in Figs. 4 and 5 whenever the cylindrical member 2 is in starting position, and when it is desired to rotate the member 2 to closed mixing position, it is only necessary to grasp one of the lugs 19 and move the same to a diametrically opposite position. Although there is very little tendency for a structure of this nature to leak, I may provide a suitable annular groove 20 in the circumference of the head 12, as shown, or in the inner circumference of the bearing portion 16, and fill this groove with a suitable ring of asbestos and graphite or any other suitable material which will make the fitting gas-tight and prevent the vaporized gases from leaking.

The lower portion of the integral housing 1 is preferably formed in the shape of a conduit 21 which extends downwardly and rearwardly whereby to conduct the combustible mixture to the burner or burners of the stove or other liquid fuel burning apparatus.

In operation, in order to start the stove or

other structure, the generator tube 5 may be moved inwardly to the position shown in Fig. 1, the member 2 having been turned to the position shown in Figs. 1 and 5. Liquid fuel is then introduced into the tube 5 under pressure, and a small amount of the liquid fuel allowed to be projected into the drip cup 11, when the valve for admitting liquid fuel to the tube 5 is closed. The fuel in the drip cup 11 may then be ignited and the heat from the open flame will soon heat the enlarged outer end of the tube 5 to vaporize the liquid fuel therein, which liquid fuel being vaporized will be projected through the orifice in the jet block forwardly against the deflector surface 13 and then backwardly over the surface of the liquid fuel in the drip cup 11, and against the generator tube 5. This rearwardly directed vaporized fuel will be in the form of a strong blast of flame which will greatly accelerate the heating of the generator tube 5 so that in a very short time the tube will be hot enough to vaporize any liquid fuel passed therethrough. When the liquid fuel in the dripping cup 11 has been practically burned up the operator merely rotates the member 2 one hundred and eighty degrees by moving the arm 17 from the position shown in Fig. 5 to a diametrically opposite position so that the member 2 completes the housing 1, as shown in Fig. 2. The tube 5 is then withdrawn to the position shown in Fig. 2, the fuel inlet valve opened, and the vaporized fuel projected from the jet block 6 will mix with air entering the passageways 3 to form a combustible mixture which will be conducted forwardly and then downwardly and backwardly through the conduit 21 and into the burner 7 where such completely vaporized fuel will be ignited to heat the tube 5 and insure continued operation of the apparatus.

It will thus be seen that I have provided a starting and mixing unit which is extremely simple and compact in design and which comprises only two parts, an integrally cast housing, and an integral cylindrical starting unit. The design of such two parts is such that very little, if any, machining is necessary, the only machining required in any case being the rough machining of the cooperating cylindrical surfaces.

What I claim is:

1. A combined starting and mixing chamber for liquid fuel burners, comprising a housing provided with a passageway for conducting air to the vaporized fuel and another passageway for conducting the vaporized fuel towards the burner or burners, and a combined closure and starting member rotatably mounted on the said housing and adapted to close the upper part of said second passageway from the atmosphere and place the same in communication with said first passageway in one position of rotation.

2. A combined starting and mixing cham-

- ber for liquid fuel burners, comprising a housing adapted to cooperate with a generating member and provided with a rotatable starting member, said starting member and said housing having semi-cylindrical concentric walls, and means for rotating said starting member to one position whereby the walls of said starting member will be complementally positioned, and to another position whereby said semi-circular walls will be oppositely positioned to form a completely closed housing to conduct the generating gases to the burner or burners. 5
3. A combined starting and mixing chamber for liquid fuel burners, comprising a cylindrical starting member having a portion of its surface shaped to form a priming cup and a portion thereof cut away, a housing for supporting said starting member having surfaces thereof cylindrical in shape whereby to form bearing supports for said starting member, a passageway in said housing leading away from said cylindrically shaped portion, and means for rotating said starting member, said starting member being adapted in one position to close said passageway, and in another position to uncover said passageway. 10
4. A combined starting and mixing chamber for liquid fuel burners, comprising a housing adapted to receive a generating member and including a starting member rotatably mounted to rotate about said generating member as an axis, said starting member being shaped and movable to one position to form a fuel pan for preheating the generating member, and to another position for closing the housing to conduct the generated gases to the burner or burners. 15
5. A combined starting and mixing chamber for liquid fuel burners, comprising a housing provided with an entrance head for receiving a generating member, a starting member rotatably mounted and provided with a cylindrical portion for also receiving said generating member, and means for rotating said starting member approximately 180° about said generating member as an axis to close said housing and form a wall of a passageway for conducting the generated gas to the burner or burners. 20
6. A combined starting and mixing chamber for liquid fuel burners, comprising a housing provided with an aperture for receiving a generator member and a passageway for conducting the generated fuel to the burner or burners, and an integral starting member shaped to form a fuel pan and a blast deflector, said starting member being adapted to be rotated about said generator member as an axis to open or close said passageway. 25
7. A combined starting and mixing chamber for liquid fuel burners, comprising a housing adapted to receive the outlet of a generator member and for conducting vapor- 30
- ized fuel from said generator member to the burner or burners, a pivotally mounted flame deflector having a cylindrical surface adapted to complementally fit with a cylindrical surface of said housing, a fuel pan secured to said blast deflector, and means for moving said fuel pan and blast deflector to a position below and in front of said generating member whereby to initially deflect the vaporized fuel issuing from said member back against said member in the form of flames to accelerate the starting thereof. 70
8. A starting device for liquid fuel burners of the type having a generator tube and a conduit for mixing and conducting the vaporized fuel from the generating tube towards the burner manifold, comprising a combined blast deflector and fuel pan substantially cylindrical in shape and movable as a unit about an axis in alignment with said generator tube and within said conduit to a position in front of and below the generator tube, the fuel pan producing flames for heating up said tube, and the blast deflector deflecting vaporized fuel issuing from said tube back against the same in the form of flames to accelerate the heating of said tube. 80
9. A starting device for liquid fuel burners of the type having a single main generator, and a conduit for conducting the vaporized combustible fuel from the generating tube toward the burner or burners, comprising a blast deflector rotatably but permanently positioned adjacent the end of the generator tube, means secured to the blast deflector for closing off the conduit for conducting the vaporized fuel towards the burner or burners, and means for effecting relative movement between the generating tube and the rotatable blast deflector whereby the blast deflector will be positioned in front of the generating tube for deflecting the vaporized fuel issuing from the generating tube downwardly and backwardly in the form of a blast against the tube itself. 85
- In testimony whereof I affix my signature.
